(57) **CLAIM**

The ornamental design for a light barrier for gates, as shown and described.

DESCRIPTION

FIG. 1 is a front perspective view of a new design for a light barrier for gates design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is left elevation view thereof; and,

FIG. 8 is a right elevation view thereof.

The phantom lines showing indicia on the front of the light barrier for gates are included for the purpose of illustrating portions of the light barrier for gates and form no part of the claimed design.
